UNITED STATES PATENT OFFICE

JOHN A. SERRELL, OF PASSAGRILLE, FLORIDA, AND JAMES L. FITTS, OF PENSAUKEN TOWNSHIP, MERCHANTVILLE, CAMDEN COUNTY, NEW JERSEY; SAID FITTS AS-ASSIGNOR TO WARREN WEBSTER & COMPANY, A CORPORATION OF NEW JERSEY

VACUUM OPERATED WATER LIFTING APPARATUS

Application filed February 5, 1925. Serial No. 6,939.

It is frequently the case in vacuum systems of steam heating in which a partial vacuum is maintained in the return mains of the system that the water of condensation which 5 passes into said mains is required to be lifted from a lower to a higher level for purposes of convenient disposal or for other reasons, and it is the object of our invention to provide a suitable means associated with and 10 combined into the return piping of a steam heating apparatus whereby such results may be obtained with the employment of a relatively low vacuum.

Heretofore, in vacuum systems of steam 15 heating, it has been necessary under special conditions to cause water of condensation in the return pipes to be lifted from one level to a higher level during its travel toward the discharge end of the system or for raising 20 condensed water collections in the returns from the lowest level to a higher level where the vacuum pump was located and from 25 which level it was discharged either for return to the boiler or for other final disposal, but in such practice it has been customary to maintain a sufficient vacuum in the return 30 pipes at the higher level to provide an absolute pressure less than that which would be required to balance or exceed the weight of the vertical column of condensed water thus required in passing from the lower to the upper level in its movement for elimination or discharge from the heating system. While, in such systems, there is some air 35 passing into the returns along with the water of condensation and is thus mixed with the water and assists it to some extent in passing through "lifts" when they occur in such parts of the system where the air is necessarily in quantity sufficient for the purpose, but at such levels as are below the vacuum pump and in the return pipes directly leading to the pump, in which the air accumulations are inadequate in quantity to materially assist in raising the water to the pump especially where the water column or "lift" would equal the height of the basement or lower floor below the level of the vacuum pump or discharge from the return pipes of 40 the system and it is, more particularly, to en-

able the effective lifting of this water of condensation that our invention is directed.

It will be manifest that where the vacuum pump may be arranged at the lowest level or thereabouts of the return pipes of the heating system, there will be no difficulty in discharging the water of condensation in an efficient manner; but when the steam mains and return pipes are branched downward to insure heating at a level below the vacuum 55 pump, the air from the main part of the system passes directly to the pump at its higher level and consequently there will be too small a quantity of air at the lower level to sufficiently subdivide the water to lighten the 60 composite column of the mixture to enable it to respond in its upward flow to the normal vacuum which the system would require. This would be more apparent when the water of condensation from the upper portion 70 of the system is permitted to find its way, in whole or in part, to the lower level under consideration, because in such case the greatest part of the air would be, in effect, short-circuited and removed at the higher or pump 75 level. Our improvements fully overcome the difficulties thus pointed out and insure efficient heating by radiators below the vacuum pump or discharge level equal to that which may be had from the radiators at or above the said pump level.

Our invention comprehends a controlled supply of air or gas into the lower part of the lift return pipe on the upper end of which a partial vacuum is maintained by 80 a suitable pump or other means, and so operating that the vacuum will cause an inflow of air at or near the base of the water column and, intermingling with the water, cause its subdivision and lessening in volume with the result that the buoyancy of the air supplemented with the exhausting action of the vacuum pump will, with a relatively small vacuum or absolute pressure, sustain and upwardly move a relatively high 85 column of water and air mixture. This is insured by reason of the fact that the static head which would be effective in any such given column, if water alone were employed, is greatly lessened in weight by the intro- 90

duction of the air; and this air admixture is made possible by the presence of the vacuum acting upon the upper end of the column or lift.

Our object is, furthermore, to so regulate the air inflow that it shall be only such, as with a predetermined extent of vacuum, the necessary height of lift can be insured, it being understood that the smaller the air admission possible with the vacuum required 10 the more efficient the results.

With the above and other objects in view, the nature of which will be more fully understood from the description hereinafter, 15 the invention consists in the novel construction of vacuum operated water lifting apparatus, as hereinafter more fully described and defined in the claims.

Referring to the drawings: Fig. 1 is a 20 vertical section through a portion of a building equipped with steam heating apparatus embodying our invention; Fig. 2 is an elevation of the more particular parts constituting our improvements which are embodied in the general heating system; Fig. 25 3 is a vertical section through the nozzle for supplying air into the water column of the "lift" forming a part of the structure of Fig. 2; Fig. 4 is a vertical section through the controlled inlet for the air which is supplied to the nozzle of Fig. 3; Fig. 5 is a 30 vertical section of a trap-like foot fitting for the "lift" and which is also adapted as the top fitting thereof; Figs. 6 and 7 are vertical sections of modified forms of air and 35 water mixers which may be substituted for the mixing nozzle structure shown in Fig. 3; and Fig. 8 is a vertical section of an automatic means for controlling the air supply 40 to the air mixing nozzle.

Fig. 1 is a typical illustration of a vacuum steam heating system in which V is a 45 mechanical pumping device for producing a partial vacuum within the system. 2 are radiators at or above the lowest of the return mains 6 and 3 is a radiator which is located at a level lower than the pump. The steam supply from a generating source, such as a boiler B, (or the steam exhausted from 50 an engine or power unit), passes into the radiators through supply pipes 4. In the radiators, the steam parts with its latent heat, forming water of condensation which, passing from the radiators through traps 55 5, enters the return pipes or mains 6, and thence passes to the vacuum pump which discharges to an open air and water separating tank of other receptacle (not shown) provided for the purpose of receiving the 60 water of condensation, or said water may be discharged as waste.

Referring more particularly to our improved lift 7 and its connection in respect to the radiator 3 arranged at a lower level than 65 the vacuum pump V, it will be seen that said

radiator is located approximately at a lower level constituting the basement beneath the floor on which the vacuum pump is located, and the lift 7 is arranged as a connection between the return main 6a from the radiator 70 3 at this lower level and the return pipe 6 from the radiator 2 leading to the vacuum pump on the floor next above the basement, thereby requiring that the water of condensation shall be lifted approximately ten feet, 75 more or less, under the effective vacuum of the pump and the buoyant action of the air which is admitted into the lift pipe to lighten the water column therin.

Referring more specifically to Fig. 2, it 80 will be seen that the water from the lower return pipe 6a is conveyed upward through the vertical lift pipes 10 and 10a to the return pipe 6 and a higher level, namely, that at 85 which the vacuum pump is located. These pipes 10 and 10a provide a column through which the water is to be conveyed and may amount to ten feet more or less, corresponding to the height of the basement or distance 90 between the levels of the return pipes 6 and 6a. At the bottom of the water column and connecting with the pipe 10a is a foot fitting 8, shown more fully in Fig. 5, and from 95 which it will be seen that the water of condensation from the return pipe 6a is delivered into the bottom of the vertical passage 8b which communicates directly with the bottom of the pipe 10a and, at the same time, the shape of this fitting constitutes a well for the 100 collection of the water immediately below the lift pipe and a trap through which the air from the return pipe 6a may be drawn under the influence of the vacuum, and thereby be subsequently guided upwardly together with 105 the water flowing through the lift. This 110 foot fitting 8 may be provided with a cleaning aperture at the bottom of the well portion and normally sealed with a plug 8c. By reason of the shape of this foot fitting, the water of condensation which may find its way into the return pipe 6a may be almost entirely removed through the lift, since any material 115 collections of water will maintain the bottom of the passage 8b at the base of the lift in a sealed condition, and said water will be moved upward under the influence of the lift mechanism so long as the bottom of the lift passage is sealed with water.

At the upper part of the lift pipe 10 is arranged, at 8a, a duplicate of the fitting 8 only that it is inverted with the result that it provides a delivery outlet into the return pipe 6 which is somewhat lower than the top of the water column as constituted by the said fitting, whereby the water which reaches the top 120 is free to pass therefrom into the return pipe 6 toward the pump under the influence of the vacuum and, at the same time, prevent any 125 backflow from said return pipe 6 into the lift 130 pipe 10.

pipe 10 by reason of drainage from the upper return pipe 6 at times when the lift was not in actual operation owing to lack of water or condensation in the lower return pipe, as when the radiator 3 was shut off.

The vertical pipes 10 and 10 α are connected by a body casting 11 which is conveniently arranged close to the lower fitting 8 by making the pipe 10 α short as compared to the pipe 10. The body 11 is hollow and of the general construction shown in Fig. 3. This body 11 has a lateral opening into which is screwed an air supply pipe 14 α , the same being fitted at its inner end with an upwardly directed air nozzle 12, said nozzle being preferably tapered and extending somewhat into the lower end of the pipe 10 and providing between it and the interior wall of said pipe an annular water passage 13. The lower part 20 of the pipe 10 is preferably reamed out on a taper to substantially correspond to the taper of the nozzle, and whereby the water rising through the body may pass freely upward about the end of the air nozzle 12. The pipe 14 α connects with the bottom of a vertical air pipe 14 which, at its upper end, provides an intake for the air which is to be delivered from the nozzle 12. This intake should preferably control the inflow of air to provide the necessary buoyancy to the water which is to be elevated through the lift or stand pipe 10 under a given vacuum in the system. The preferred construction of this intake for the air is illustrated in Fig. 35, and comprises a chamber 15 attached to the upper end of the air pipe 14, in which a transversely arranged plate 16 is clamped, said plate having an orifice 17 through which air passes into the vertical air pipe with the desired freedom necessary. The size or area of this orifice 17 and that of the mixing nozzle 12, as well as the size or area of the vertical lift pipe 10 above the said nozzle, are suitably proportioned to obtain the raising 40 of the largest quantity of water with a minimum quantity of air when operating at a suitable vacuum in the return pipe 6. It is highly desirable to keep the volume of air which enters the orifice 17 at a minimum 45 consistent with the effective lifting of the water so as to prevent the vacuum pump being required to handle any larger volume of air than is absolutely necessary to accomplish the work required in the lift while, at the same time, maintaining the desired vacuum in the remaining parts of the heating system.

The plate 16 is clamped in the chamber 15 by a ring cap 20 which is screwed upon the body and which, in addition to clamping the plate 16 in position, also clamps a perforated plate or metal screen 19 and a disk of porous material 18, such as felt, in position to permit the entrance of the air to the orifice in the plate but preventing the pas-

sage of dirt or dust which might clog the orifice 17. A spacing ring 19 α is inserted between the metal screen 19 which supports the porous material 18 and the rim of the plate 16, so as to provide an air space between the two which will furnish a greater area for the passage of air through the porous material or filter than the area of the orifice 17, as would be necessary in view of the fact that the porous material 18 or filter would retard the free passage of the air. We do not restrict ourselves to the particular construction of air intake here shown, but have found that it is excellently adapted to the purposes of the invention. The plate 16 is removable, so that, in practice, the size of the orifice 17 required may be provided by substituting a plate or diaphragm 16 having a larger or smaller orifice, as may be necessary. It will be understood, however, that this orifice may be adjustable and as a means for accomplishing such adjustment, we have shown a modified construction in Fig. 8 which not only permits of the adjustment of the size of the orifice for the inflow of air, but also provides capacity for an automatic adjustment of the orifice in accordance with the requirements of the system in operation.

Referring to Fig. 8, the chamber 15 is connected with the top of the air pipe 14 and is fitted with a screen or filter 19 clamped in position by the ring cap 20. This ring cap also clamps the diaphragm 16 α in position corresponding to the plate 16 in Fig. 4. The diaphragm plate 16 α is provided with a central aperture 17 α and entering said aperture is a conically pointed end of a screw 21, which extends through the wall of the chamber 15 so as to be adjustable from the outside and may be locked in adjusted position by a lock nut 22. It will be seen, furthermore, that the diaphragm 16 α is preferably made in the form of a bellows 16 β , so as to be expandible with capacity for movement of the plate 16 α and its orifice 17 α toward or from the conical end of the screw 21. Primarily, it will be understood that the adjustment of the screw 21 in the orifice 17 α will regulate or control the size of the air passage and in this manner will give normal capacity 110 of adjustment for any fixed conditions as to lift and vacuum. However, the device, as shown, has capacity for automatic adjustment under influence of the variable conditions which may arise in the operation of 115 the system.

The physical law governing the flow of a fluid through an orifice is, that the flow by weight of the fluid through such orifice is proportional to the square root of the pressure difference between the two sides of the orifice and it, therefore, follows that should the vacuum increase in the system under consideration, the absolute pressure on the underside of the diaphragm 16 α will decrease rela- 120

tively to the atmospheric pressure above said diaphragm, and consequently there would be an increased passage of air through the orifice 17a whereas a lesser quantity of air 5 would satisfy the requirements of the lift; and under such increase of vacuum, the diaphragm 16a would be drawn slightly downward toward the conical end of the screw and thereby automatically reduce inflow of 10 air whereby its volume may be proportional to the duty required of it. In other words, the higher the vacuum exerted on the upper part of the lift pipe 10, the less the quantity of air which is required to assist in the lifting 15 of the water, and vice versa. Any other automatic means for controlling the quantity of air admitted to the lift pipe to compensate for variations in the vacuum available or for variations in the extent of vacuum may be 20 employed in lieu of that shown by way of example.

While we have shown in Fig. 3, a suitable means for supplying the air at atmospheric pressure into the lift pipe 10, we do not limit 25 ourselves to the precise construction therein disclosed, as similar results may be secured by the modifications illustrated in Figs. 6 and 7. In Fig. 6, we have shown the nozzle 12a as comprising a vertical tube open at the bottom 30 and having spraying orifices at the top, the upper end of said tube being arranged adjacent to the bottom of the lift pipe 10, so as to leave an annular passage 13 between it and the spraying nozzle. In this construction, the air which enters by the pipe 14a will pass upwardly and out through the orifices 35 in the nozzle 12a, and thus be commingled with the water rising through the annular passage 13. Air may also pass through the bottom of the tubular part 12a into the chamber 11 and be thus mingled with the water rising from the tubular section 10a and said mixture of water and air commingled with the mixture produced adjacent the upper part 40 of the nozzle 12a, the associated mixtures thereafter being delivered into the lift pipe 10. We do not restrict ourselves to the length to which the tubular part 12a extends upwardly in respect to the pipe 10 or downwardly in respect to the pipe 10a, as the length of said tubular nozzle part may be varied, as desired.

In respect to the construction shown in Fig. 7, the general construction is such that 55 the body part 11 provides a chamber into which the air from the supply pipe 14a is received and, furthermore, the water pipe 10a is extended upwardly through the air chamber to a point adjacent to the bottom 60 of the lift pipe 10; and the pipe portions are so constructed as to provide a nozzle 12b in alignment with the bottom of the pipe 10 so that the water in flowing upward from the pipe 10a into the pipe 10 will create a suction 65 to some extent through the annular

conical aperture 13a surrounding the nozzle portion 12b and opening into the lower portion of the pipe 10, to assist in the intermingling of the air from the air chamber in the body 11 and the water which is passing 70 upward through the nozzle 12b. Other forms of air and water mixers may be employed in lieu of any of those herein illustrated, so long as they provide a proper commingling of air with the water at the lower 75 part of the lift pipe 10 for the purposes hereinbefore set out.

It will be noted that in Fig. 2 the air supply pipe 14 extends somewhat above the level of the return pipe 6 so that it reaches a point 80 somewhat higher than the top of the lift pipe 10 and the reason for this construction is that should from any cause the vacuum pump cease to operate and the water in the return 6 accumulate and flow down into the lift pipe 85 10, then and in that event, the water may rise in the pipe 14 to the level of the return pipe 6 without overflowing from the orifice 17 at the upper part of said pipe 14. We, however, do not restrict ourselves to the height 90 of the said pipe 14, as during normal operation of the apparatus, the inflow of air through the pipe 14 will prevent the outlet of water therethrough.

In the operation of a vacuum steam heating system having one or more lifts of the character here set out, the action is as follows: The vacuum pump V is started and a partial vacuum is produced in the return part of the system in the manner customary 95 with heating systems of this character; and, at the same time, air in measured quantities flows through the orifice 17 of the air intake devices for the lift 7. Steam being admitted to the steam supply pipes 4 from the boiler or other source B, enters the radiators 2 and 3 under manual control; and being condensed therein, the water of condensation flows through the automatic traps 5 into the return mains 6 and 6a, and in the case of the latter, the water passes into the foot fitting 8 where it accumulates as indicated in Fig. 5. The pressure differential between the bottom and top of the lift pipes 10 and 10a cause the water from the well in the lower fitting 8 to rise above the level of the air nozzle 12 of the air mixer 9, where the air entering lift pipe 10 from nozzle 12 mixes with the water and thereby reduces the density of the column constituting the fluid content 120 within the said lift pipe and causing said column to continue to flow upwardly at an increasing velocity. When the mixture of water and air reaches the upper fitting 8a, it passes over the weir 8e therein and into the horizontal return main 6 leading to the vacuum pump V. As indicated in Figs. 2 and 3, the air A, being lighter than the water W, tends to buoy it up and carry it upward, the water being largely lifted in more or less sep- 125 130

arated masses due to the presence of the air volumes intermingled therewith.

As the quantity of water of condensation varies during the early portion of the "heating up" period, when steam is being first admitted into the cold radiators with a maximum production of water of condensation, it is at this time most important to admit the air through the orifice 17 into the pipe 13 leading to the air nozzle 12, to enable the elevation of the large volumes of water of condensation which finds its way to the lowest return pipes of the system. Efficiency of the apparatus is required more particularly at this period of the operation of the heating system when the duty put upon the lift is exceptionally heavy and the capacity of the vacuum pump is taxed to a high degree in handling the water as well as the normally liberated air from the condensed steam.

The degree of vacuum necessary to lift water, if in a solid column, is approximately equivalent to a pressure of one inch of mercury to each foot of vertical height of the column, so that for a vertical lift of say ten feet, an absolute pressure equivalent to ten inches of mercury is required as a vacuum below atmospheric pressure, and with some excess to insure a rapid flow of the water in a system such as a vacuum steam heating system.

With our improved devices herein set out, the actual vacuum required to start the lift of the water through a height of ten feet may be reduced to approximately one-half of that which would be required if the water was in a solid column and, therefore, after starting the column through the employment of air, the vacuum required may be reduced to approximately two and one-half inches of mercury or about one quarter of the vacuum which would have been required to lift the water if the same had been in a solid column. Under such conditions, a slightly greater vacuum at the pump is normally effective throughout the returns of the system other than that particular portion in which the lift is located. The present invention operates as an efficient means for elevating water in the returns of a steam heating system by means of air at atmospheric pressure entering the return mains in controlled volumes when a pump or other means is used for exhausting the air from the returns of said system.

While we have described our invention in connection with a relatively large lift equivalent to the height of the basement, we do not restrict ourselves to a special use of such a lift, either as to size or as to its use in a vacuum system of steam heating, as the principles involved in our improved lift may also be put into operation when the lift, such as shown in Fig. 2, receives a water supply to the pipe 6a from any source and a partial

vacuum is maintained in the upper pipe 6, and wherein the air admitted to the lift pipe is at atmospheric pressure. It will be further understood that in a steam heating system or any other purpose, a lift of this character may be arranged in the system at various levels, as may be required, for example, as indicated at 7 and 7a in Fig. 1, though in the particular illustration, the lift 7a is relatively small.

While we have described our invention as applicable to a steam heating system, the claims of the present application are directed to a vacuum operated water lifting apparatus without regard to its particular use, and we, therefore, do not make any claim in this application limited to a steam heating system, as the same will form subject matter of a separate application.

We have described our improved means and method in that particularity which we deem to be the best exposition of our invention and that which we prefer in commercial practice, but we do not restrict or confine ourselves to the minor or secondary details, as such are susceptible of modification and may be resorted to as matters of mechanical skill and without a departure from the spirit of the invention.

Having now described our invention, what we claim as new and desire to secure by Letters Patent is:

1. Means for lifting water from one level to a higher level, comprising a lift pipe, a pipe at the low level for supplying water to the bottom of the lift pipe, a pipe at the higher level in communication with the upper part of the lift pipe and in which a partial vacuum is maintained, a vacuum creating means for maintaining a partial vacuum in the pipe at the higher level and withdrawing water so lifted together with the associated air from said pipe at the higher level, and means for introducing air into the water in the lower part of the lift pipe, the said means for admitting air to the lower part of the water lift pipe being provided with an upright air pipe extending to approximately the upper part of the water lift pipe and having means at its upper end to admit air in restricted quantities.

2. Means for lifting water from one level to a higher level, which comprises a lift pipe, a pipe at the higher level in communication with the upper part of the lift pipe and in which a partial vacuum is maintained, a vacuum creating means for maintaining a partial vacuum in the pipe at the higher level and withdrawing air and water therefrom, means for introducing air into the water in the lower part of the lift pipe, said means having a communication with the atmosphere, and a trap-like structure providing a well arranged at the bottom of the water lift pipe into which the water is trapped for its supply to the said lift pipe.

and a horizontal return pipe supplying water of condensation into the said trap-like structure.

3. The invention according to claim 1, wherein the means for introducing air into the water comprises an annular water passage into which an air nozzle extends forming an ejector for producing a suction upon the air by the upwardly rising water.

10 4. Means for lifting water from one level to a higher level, which comprises a lift pipe, a pipe at the lower level for supplying water to the bottom of the lift pipe, a pipe at the higher level in communication with the upper part of the lift pipe and in which a partial vacuum is maintained, a vacuum creating means for maintaining a partial vacuum in the pipe at the higher level and withdrawing air and water therefrom, means for introducing air into the water in the lower part of the lift pipe, said means having a communication with the atmosphere, and automatically adjustable means governed by the pressure conditions within

15 the means for introducing the air into the water in the lower part of the lift pipe for controlling the quantity of air admitted.

5. Means for lifting water from one level to another, which comprises a lift pipe, a pipe at a low level for supplying water to the bottom of the lift pipe, a pipe at a higher level in communication with the upper part of the lift pipe and in which a partial vacuum is maintained, a vacuum creating means

20 for maintaining a partial vacuum in the pipe at the higher level, means for introducing air into the water in the lower part of the lift pipe, and a communication between the air introducing means and the atmosphere,

25 comprising a pipe extending to approximately the level of the upper end of the lift pipe and having thereat an aperture proportioned to supply air in measured quantities under the influence of the partial vacuum

30 existing in the pipe at the higher level with which the upper end of the lift pipe communicates.

6. The invention according to claim 1, wherein further, the means for controlling the admission of air to the upper end of the upright air pipe includes a thin apertured disk and detachable means for clamping the disk upon the upper end of the upright air pipe whereby disks with different sized apertures may be substituted as required according to the extent of the partial vacuum and the height of the column of water in the lift pipe.

7. Means for lifting water from one level to another, which comprises a lift pipe, a pipe at a low level for supplying water to the bottom of the lift pipe, a pipe at a higher level in communication with the upper part of the lift pipe and in which a partial vacuum is maintained, a vacuum creating means

for maintaining a partial vacuum in the pipe at the higher level, means for introducing air into the water in the lower part of the lift pipe, and a communication between the air introducing means and the atmosphere comprising a pipe extending to approximately the level of the upper end of the lift pipe and having thereat an aperture proportioned to supply air in measured quantities under the influence of the partial vacuum existing in the pipe at the higher level with which the upper end of the lift pipe communicates, and wherein further, automatic means are provided for adjusting the admission of air to be mixed with the water in the lift pipe.

In testimony of which invention I hereunto set my hand.

JOHN A. SERRELL.
